PALLET FOR STORING AND TRANSPORTING TIRES

Emanuel J. Zinna, 28 Holly Drive,
Sayville, N.Y. 11782

Filed Dec. 18, 1974, Ser. No. 533,865

Term of patent 14 years

Int. Cl. D9—99

U.S. Cl. D12—53

FIG.1

FIG. 1 is a right side elevational view of a pallet for storing and transporting tires showing my new design, the left side being a mirror image thereof;

FIG. 2 is a front elevational view thereof, the rear elevational view being a mirror image thereof; and

FIG. 3 is a perspective view thereof.

I claim:

The ornamental design for a pallet for storing and transporting tires, as shown.
